Primary Examiner — Cynthia M. Chin

(57) **CLAIM**

The ornamental design for a toy vehicle body, as shown and described.

DESCRIPTION

FIG. 1 is a perspective view of a toy vehicle body showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the toy vehicle body where the toy vehicle body is in a first exemplary configuration of use;

FIG. 10 is a perspective view of the toy vehicle body where the toy vehicle body is in a second exemplary configuration of use;

FIG. 11 is a perspective view of the toy vehicle body where the toy vehicle body is in a third exemplary configuration of use;

FIG. 12 is a perspective view of the toy vehicle body where the toy vehicle body is in a fourth exemplary configuration of use;

FIG. 13 is an enlarged partial view taken from the left side of FIG. 1; and,

FIG. 14 is an enlarged partial view taken from the right side of FIG. 2.

The dash-dot broken lines represent the boundaries of the enlarged partial views of FIGS. 13 and 14. The broken lines in FIGS. 1-8 and 13-14 represent portions of the article that form no part of the claimed design. The broken lines in FIGS. 9-12 represent exemplary environment in which the article resides. None of the broken lines form a part of the claim.

1 Claim, 14 Drawing Sheets
